E. ROESSNER.
HAIR CURLING DEVICE.
APPLICATION FILED JUNE 11, 1921.

1,406,083.

Patented Feb. 7, 1922.

UNITED STATES PATENT OFFICE.

ENA ROESSNER, OF NEW YORK, N. Y.

HAIR-CURLING DEVICE.

1,406,083.

Specification of Letters Patent. Patented Feb. 7, 1922.

Application filed June 11, 1921. Serial No. 476,702.

To all whom it may concern:

Be it known that I, ENA ROESSNER, a citizen of the United States, and a resident of the borough of Manhattan, city, county, and State of New York, have invented certain new and useful Improvements in Hair-Curling Devices, of which the following is a specification.

The object of my invention is the production of a simple, inexpensive, but effective hair curling device that may be conveniently manipulated, and which is adapted to the production of marcel waves, spiral curls, bob curls, etc., as hereinafter fully set forth, the invention consisting in the specific construction, combination, and arrangement of parts described and claimed, and a distinctive feature being the formation of the guard yoke and snap loop of a single piece of metallic wire bent into permanent shape and having sufficient elastic resilience to maintain such normal shape while admitting of the facile snap-locking and release of the otherwise free end of the hair wind spindle as required in use.

In the accompanying drawings,

Fig. 1, is a side elevation of my improved hair curling device, closed;

Fig. 2, is an end elevation of the parts as shown in Fig. 1, looking in the direction of the arrow *a*;

Fig. 2^a, is a view like unto Fig. 2, with the end of the wind spindle released from the snap loop;

Fig. 3, is an elevation of the device, closed as in Fig. 1;

Fig. 4, is a view of a modification in the construction of the guard yoke and wind spindle, the latter being broken away in part and turned in alignment with the guard yoke;

Fig. 4^a, is a sectional elevation taken upon plane of line 4^a—4^a, Fig. 4;

Figs. 5 and 6, are sectional details showing modifications in the means of articulately connecting the wind spindle to the guard yoke;

Fig. 7, is a cross section taken upon plane of line 7—7, Fig. 1.

The guard yoke G, is formed of a single piece of elastic resilient material, such as metallic wire of suitable gauge, bent up and set into permanent shape which is preferably that of an elongate rectangular parallelogram as shown in Figs. 1, 3 and 4, of the drawings.

The wind spindle S, may be either solid or hollow, preferably the latter as shown in all but Figs. 4 and 4^a. It may be conveniently and economically made of a single piece of sheet metal bent into cylindrical shape in cross section as shown particularly in Fig. 7, although other material may be used, so that I do not limit myself in this respect. The hollow metallic form of wind spindle S, is however advantageous in some respects in that it is adapted to receive a heating iron of slightly less diameter which may be inserted in the spindle for the purpose of heating and thereby imparting a more permanent set to a strand of hair wound around said spindle, as indicated for instance in Fig. 3.

When the wind spindle S, is hollow as above stated, the guard yoke G, may be pivotally secured thereto at one extremity by inserting the ends *g*, *g*, through holes *s*, *s*, formed for the purpose in and near one extremity of said spindle tube S, and upsetting the said ends *g*, *g*, either by inturning them as shown in Fig. 6, or by flattening them as shown in Fig. 5, as may be found most convenient or expedient in manufacture, the result being the same in either case that the said ends *g*, *g*, of the guard yoke G, are thereby secured against displacement, and a pivotal connection is effected between the said wind spindle S, and its guard yoke G.

Or a like result may be attained in the construction shown in Figs. 4, 4^a, in which the yoke wire is passed through a perforation *s'*, (or perforations) in the end of wind spindle, and the ends brought together and welded or otherwise united integrally as at *g'*, Fig. 4, in which case the wind spindle may be either hollow as in most of the figures of the drawings, or solid, as indicated in Figs. 4 and 4^a, thereof.

The outer or free end of the guard yoke G, is bent into the form of a snap-loop *g*^x, the entrance thereto being normally slightly less than the external diameter of the wind spindle S, and the elasticity and resilience of the material of which the guard yoke G, is composed being relied upon to admit of the forcible insertion of the free end of the spindle S, into the loop *g*^x, and its retention therein until forcibly released therefrom.

The simplicity and utility of the device thus constructed is obvious. The parts may be quickly opened up either for the purpose of winding a lock or strand of hair around

the spindle or removing it therefrom,—the snap-loop g^x , readily yielding to a moderate degree of pressure, while adapted to lock the parts together with sufficient strength and tenacity to resist accidental displacement.

It may be noted in this connection that my device presents only round, smooth, surfaces for contact with the hair, thereby obviating injury thereto, while safeguarding the lock of hair wound upon the spindle against undesirable contact with extraneous objects. Furthermore the device, while simple of structure and facile of manipulation, is strong and substantial, and not liable to get out of order or deteriorate under ordinary conditions of use.

By the term "guard yoke" as used in the claims it is to be understood that I mean a yoke piece substantially such as shown with elongate side members which are essentially parallel, or approximately so, and which are united at either extremity by cross members which are rectangular as related to said elongate side members, or substantially so. Also that by the term "wind spindle" I mean to designate any suitable spool-support for the hair to be curled, substantially as herein set forth.

What I claim as my invention and desire to secure by Letters Patent is,

1. As an article of manufacture, a hair curling device of the character designated, comprising a one piece guard yoke of elastic resilient wire bent permanently into elongate substantially rectangular shape at the ends, one end being formed with a snap loop and the other constituting a fulcrum for the articular support of a wind-spindle, and said wind-spindle consisting of a sin-

gle piece of metal bent into permanent hollow cylindrical shape and pivotally attached to said fulcrum end of the guard yoke, for the purpose described.

2. As an article of manufacture, a hair curling device of the character designated, comprising a one-piece guard yoke of elastic resilient wire bent permanently into elongate substantially rectangular shape, one extremity of the yoke piece being formed into a lateral snap-loop and the ends of the wire at the other extremity of the guard yoke being upset to form fulcrum shoulders for engagement with a hollow wind-spindle, and said wind-spindle consisting of a single piece of sheet metal bent into permanent hollow cylindrical shape and pivotally attached to said fulcrum end of the yoke, substantially in the manner and for the purpose described.

3. As an article of manufacture, a hair curling device of the character designated, comprising a one-piece guard yoke of elastic resilient wire bent permanently into elongate substantially rectangular shape, one extremity of the yoke piece being formed into a lateral snap-loop and the ends of the wire at the other extremity of the guard yoke being inturned to form fulcrum shoulders for engagement with a hollow wind-spindle, and said wind-spindle consisting of a single piece of sheet metal bent into permanent hollow cylindrical shape and pivotally attached to said fulcrum end of the yoke, substantially in the manner and for the purpose described.

ENA ROESSNER.
